REFINING PRESSURE DISTILLATES

Ernest F. Engelke, Camden, N. J., assignor to
Doherty Research Company, New York, N. Y.,
a corporation of Delaware

Application April 28, 1931, Serial No. 533,399

5 Claims. (Cl. 196—24)

This invention relates to a process for refining pressure distillates and more particularly to a process for refining cracked gasolines to purify the same with respect to gum and color-forming constituents.

Anti-knock motor fuels are produced on a large scale by cracking petroleum oils at high temperature (850° to 1050° F.) by which large amounts of olefin hydrocarbons as well as aromatic hydrocarbons are formed. As is well known gasolines produced in this manner have a great tendency to turn a deep yellow color and to deposit gum. Furthermore such gasolines cannot be refined by the usual sulphuric acid method without considerable loss both in the quantity of the fuel and in anti-knock properties. Attempts have been made to refine cracked gasolines by passing them in vapor form through a bed of adsorptive clay such as fuller's earth, but this treatment is too severe, and does not prevent trouble from gum, particularly with gasolines produced by high temperature cracking.

Accordingly, the primary object of the present invention is to provide a process for refining high temperature cracked gasolines without causing a substantial reduction in their anti-knock value and which will at the same time produce a color and gum stable gasoline.

Further objects and advantages will be apparent from the following description and the appended claims.

The figure of the drawing is a diagrammatic representation or flow sheet of the process according to the present invention.

According to the process of the present invention, the pressure distillate or cracked gasoline to be stabilized as to color and gum formation is washed in an agitator chamber 2 with an alkali solution such as caustic soda solution, and is then directed by means of a pump 4 to a second agitator chamber 6, where it is treated with a sweetening agent such as sodium plumbite solution and with a slight amount of elemental sulfur to break the suspension of any lead compounds formed. The sweetened gasoline leaving the agitator 6 may be directed by means of a pump 8 into a filtering chamber 10, where it is treated with a filtering medium such as fuller's earth if desired, and is then conducted to a charge tank 12.

If the process is operated continuously, with a continuous charge of pressure distillate, the operation of the process will be as above described, but if the process is to be run in batch, return lines to both the agitators 2 and 6 are provided for the return and retreatment of the treated gasoline leaving the agitators. Furthermore a by-pass line is provided to permit the sweetened gasoline leaving the agitator chamber 6 to be run directly to the charge tank 12 without passing through the filtering chamber 10.

From the tank 12, the sweetened and filtered distillate is conducted by means of a pump 14 either to a heater 16 and thence to a treating still 18, or directly to the treating still without first passing through the heater.

An unsaturated hydrocarbon gas which is obtained as a byproduct from a cracking still during a petroleum cracking process and which has been washed with alkali to remove the sulphurous compounds therein, is conducted by means of a pump 20 through a gas purifier 22 and to heater 16 where it is mixed with the sweetened and filtered gasoline entering the heater. In the gas purifier 22 both the cracking still gas entering the system and the recirculated gas may be treated by either a solid contact purifying medium such as activated carbon, or a liquid contact purifying medium such as caustic soda solution so as to wash such cracking still gas free of entrained sulphurous gases.

The temperature of the mixture of cracking still gas and sweetened gasoline is raised in the heater 16 to that necessary to vaporize the gasoline and the mixture of vapor and gas is then conducted to the treating still 18. If the sweetened gasoline has not been run through the heater 16, but has been conducted directly to the treating still 18, it will be mixed with the gas leaving the heater prior to entering the treating still, the temperature of the cracking still gas under these circumstances being raised in the heater 16 to about 340°—400° F., and the gasoline will be completely vaporized on contact with the hot gas, the mixture of vapor and gas being conducted as before into the treating still 18.

In the treating still 18, which is in the form of a bubbler cap column, the temperature of the material under treatment will be regulated by the temperature of the super-heated steam in a steam coil 24, so as to maintain in vapor phase the desired portions of the pressure distillate. The heavy ends will be run off into a tank 26 and thence either returned for retreatment in the heater 16 in admixture with the purified cracking still gas or returned to the cracking unit. The low boiling fractions of the pressure distillate being treated in the treating still 18, which fractions are maintained constantly in the vapor phase and in admixture with the cracking still gas, are passed upwardly through a series of trays of bubbler caps 28 and a bed of oxidizing material 30 and thence from the treating still to a condenser 32. From the condenser 32, the condensed gasoline and the gas are conducted to a separating tank 34, whence the gas-free stabilized gasoline is obtained and the cracking still gas which is separated from the gasoline is conducted to the gas purifier 22, and again returned for admixture with a fresh charge of gasoline to undergo treatment in the process. The tem-

perature within the treating still 18 and return of the heavy ends from tank 26 through heater 16 to the treating still 18 are controlled so as to give in separating tank 34 a gasoline of the desired end point. The stabilized gasoline leaving the separating tank 34 may be resweetened with a sweetening agent such as sodium plumbite solution with a slight amount of elemental sulfur to break any suspension of lead compounds formed.

While the above-described process has been herein directed toward the treatment solely of a cracked gasoline or pressure distillate it has been found to be beneficial for the treatment of a blend of pressure distillate or cracked gasoline and straight run gasoline. Furthermore, it has been found beneficial to the quality of the motor fuel to blend a cracked gasoline which has undergone treatment according to the process of the present invention with a sweetened straight run gasoline and subsequently resweetening the blend thus produced. Blends produced in this manner have proved to be much more highly stabilized than either component of the blend, the blend upon being subjected to the action of strong light for a considerable period of time showing no loss in color and no formation of gum.

The sweetening agent used according to the present invention either before the distillation treatment or subsequent to the distillation and condensation of the cracked gasoline alone or of the blend of cracked gasoline and straight run gasoline, may be a sodium plumbite solution with a slight amount of elemental sulfur added. An ammoniacal copper oxide (or sulfate) solution has also been found to be an excellent sweetening agent and may be used in place of the sodium plumbite solution and elemental sulfur in any of the above sweetening or resweetening steps.

The bed of oxidizing material 30 is composed of a superoxide of a heavy metal such as MnO_2 or PbO_2 which acts to oxidize any sulfurous material remaining in the vapors being treated in the treating still 18 and also aids in the stabilization of the pressure distillate. If, after a period of use these superoxides require regeneration, such a regeneration of the superoxides may be effected during the operation of the process by introducing air into the treating still 18 at the zone of oxidation.

The heat within the still promotes the combination of the oxygen of the air with the sulfur held within the zone of oxidation to form sulfurous compounds, the oxygen of the air replacing the sulfur of the sulphide compounds of the heavy metals formed.

While the process according to the present invention has been described in connection with the treatment of pressure distillate or cracked gasoline with an alkali wash, a sweetening agent, and a filtering material prior to the distillation in admixture with a cracking still gas, it is to be noted that any or all of these steps may be omitted if such a course is considered to be advantageous under specific conditions. It has been found that some gasolines do not require a preliminary sweetening and in such cases a preliminary sweetening may be omitted.

The process according to the present invention will be found to be of considerable advantage in stabilizing a cracked gasoline or a blend of cracked gasoline and straight run gasoline as to color and gum formation while the treated gaso-

line still retains its high anti-knock value. In most cases the material which has been treated according to the process described herein will remain stable for a period of two years or more without an appreciable change in color or the slightest formation of gum and will retain its value as an anti-knock motor fuel. In certain cases however, where a slight precipitation is noticed after an extended period of storage the precipitate will be found to be in the form of a liquid, and as such has no harmful effect in the motor fuel. No solid or sticky gum is formed.

From various tests that have been made it would appear that the free hydrogen or unsaturated hydrocarbon content of the cracking still gas reacts with the unstable constituents of the pressure distillate to form a gasoline that is stable with respect to color change and gum formation. While the best results have been obtained from the use of gas from a cracking still, favorable results have also been obtained from the use of other hydrocarbon gases containing free hydrogen or unsaturated constituents.

Having described the invention in its preferred form what is claimed as new is:

1. In the process of refining pressure distillate, without substantially reducing its anti-knock value by the use of concentrated acid, for the purpose of sweetening the distillate and rendering it gum stable, the steps which consists in sweetening the distillate by passing it in intimate contact with an alkaline sweetening agent, fractionally distilling the resulting sweetened distillate while maintaining it in intimate contact with a cracked hydrocarbon gas substantially free of sulphur compounds, and carrying out said fractional distillation at a temperature not substantially exceeding 400° F.

2. The process defined by claim 1 in which the cracked hydrocarbon gas used in the distilling operation is passed in a closed cycle which includes a gas purifying zone.

3. In the process of refining pressure distillate, without substantially reducing its anti-knock value by the use of concentrated acid, for the purpose of sweetening the distillate and rendering it gum stable, the steps which consist in blending a pressure distillate with a straight run gasoline distillate, sweetening the resulting blended distillates, fractionally distilling the sweetened blend in the presence of and in intimate contact with a purified cracking still gas substantially free of sulphur compounds, and carrying out said fractional distillation at a temperature not substantially exceeding 400° F.

4. The process defined by claim 3 in which the cracking still gas used in the distilling operation is passed in a closed cycle which includes a gas purifying zone.

5. In the process of refining pressure distillate, without substantially reducing its anti-knock value by the use of concentrated acid, for the purpose of sweetening the distillate and rendering it gum stable, the steps which consist in blending a pressure distillate with a straight run gasoline and subjecting the blend thus produced to the action of an alkali solution and a plumbite solution, fractionally distilling the sweetened blend in the presence of cracking still gas at a temperature not substantially exceeding 400° F., and passing the vapors of distillation through a mass of oxidizing material comprising a superoxide of a heavy metal.
